UNITED STATES PATENT OFFICE.

NOAH S. AMSTUTZ, OF CLEVELAND, OHIO.

PROCESS OF AND APPARATUS FOR ELECTRICALLY REPRODUCING IRREGULAR OR UNDULATING SURFACES.

SPECIFICATION forming part of Letters Patent No. 448,404, dated March 17, 1891.

Application filed August 19, 1889. Serial No. 321,254. (No model.)

To all whom it may concern:

Be it known that I, NOAH S. AMSTUTZ, a citizen of the United States, residing at Cleveland, in the county of Cuyahoga and State of Ohio, have invented certain new and useful Improvements in a Process of and Apparatus for Electrically Reproducing Uneven, Irregular, or Undulating Surfaces; and I do hereby declare that the following is a full, clear, and exact description of the invention, which will enable others skilled in the art to which it appertains to make and use the same.

My invention relates to a process of and apparatus for electrically reproducing uneven, irregular, or undulating surfaces; and the object of the invention is to provide a method and means whereby sketches, designs, photographs, autographic and type matter, and the like, when wrought into forms having uneven surfaces—such surfaces, for example, as are representative of light and shade and give distinct outlines of figures in impressions or prints taken therefrom—may be speedily reproduced at any distance from the sender, thus enabling an artist to visit any place, however remote from publication, and by hastily working into suitable form for transmission any sketch, picture, photograph, or the like, have the same electrically reproduced at the home office with substantially as great speed and accuracy as news is now dispatched from point to point, the reproduction, if desired, being in relief lines a complete engraving.

In the accompanying drawings, Figure 1 is a longitudinal section of a sending apparatus, and Fig. 2 is a longitudinal section of a receiving apparatus. Fig. 3 is a side elevation of the sending part of the apparatus, showing the mechanism for regulating the back and forth movements of the table carrying the model. Fig. 4 is a similar view of the part of the apparatus at the receiving-station and showing the mechanism for controlling the back and forth movements of the reproducing-table. Fig. 5 is a perspective view of the armature and its connections for reversing the direction of movements of the driving-power.

In the apparatus shown, A represents the base or bed plate common to both figures. This plate, preferably, is cast in a single piece,

as appears in each figure, and is cored out on its under side to reduce weight, as well as to afford space for certain parts of the apparatus, thus leaving the top surface free for other uses. At one end the plate A is provided with guideways *a*, such as are common to planing-machines and lathes, and in these guideways a carriage B has free longitudinal movement back and forth for a purpose hereinafter explained. This carriage has a rack *b*, beneath which a pinion *b'* on the drive-shaft *b* engages, and by which the carriage is operated. Upon the carriage and working in transverse guides therein is a table or bed plate D, which has a short step-by-step cross-feed at right angles to the travel of the carriage B. This feed transversely is effected by a screw *D'*, having a toothed head or the like, which engages an arbitrarily-placed stop on the bed plate, and which gives a certain amount of turn to the screw, and hence a certain slight lateral movement to bed D every time the carriage reaches the end of its movement in either direction. The bed D, of course, is carried to and fro by carriage B, and has its own lateral movement besides. In operation there will be a sufficient number of longitudinal movements of the carriage B to complete the work laterally as well as longitudinally, and the breadth of the work will determine the number of longitudinal movements. The lateral movement of plate D by its screw, or other artificial means used in lieu thereof, occurs at the end of each longitudinal movement of the carriage B.

The bed-plate or table D forms a support for the work F, which rests within a frame E, surrounding the same, and is held at the corners by angle-clamps *d*. The work in Fig. 2 consists in a plate of plastic material, or a plate coated or covered with such material to a sufficient depth, and in Fig. 1 is shown in bas-relief as it appears when ready for transmission or when it is finished. In Fig. 1 are shown transverse beads or ribs *e* near the end of the work. These occur only on the sending-forms and are designed to switch or reverse the power by which frame B is carried back and forth. Various forms of mechanism might be suggested to accomplish this result. In the drawings I show a simple means, consisting of a lever H, pivoted on arched ful-

crum-rest G, which is longitudinally adjustable in ways a' on the base A.

The transmitting-lever H is adjustably held on rest G by a sleeve h, and the said lever 5 vibrates on this pivot subject to a spring h², supported at one end by an adjusting-screw on a cross-piece g on rest G, and at the other end on a short standard h³, adjustable on the transmitting-lever. This spring is of course 10 of very slight tension and is meant to keep the tracing or graving tool or point h' normally down on the work.

At its outer extremity lever H has an electrical contact-point g', which is forced down 15 when the tracing-point rides up on one of the beads e and closes the circuit on the projection beneath, thus causing the motor-reversing current to be switched and the motor reversed, when the carriage will move in the 20 opposite direction. Suitable regulating mechanism is employed for this purpose, as hereinafter described.

The foregoing description in so far as mechanism is concerned relates largely to Figs. 1 25 and 2 of the drawings and to the sending and the receiving apparatus. In Fig. 1 the device is shown complete and operative, and if put in motion the carriage B would be found to travel back and forth automatically the distance 30 between the respective elevations e, between which the work is located, and the table E, carrying the work, would be gradually fed laterally until the tracing-point had traversed the entire width of the work. Thus the tracing-point would be made to describe or to 35 travel on parallel lines on such distances apart as the lateral feed-screw would provide. In some instances, as in fine work, these lines would have scarcely a perceptible distance 40 between them, and the distance may be made greater or less, according to the quality of the work to be done.

Now, assuming that the work in Fig. 1 represents a bas-relief of a photograph and the 45 tracing-point is in position at one side to begin the back-and-forth movement over the surface of the work, as above indicated, and this surface is to be exactly reproduced at a distance from the sending-point, we find in 50 Fig. 2 an apparatus upon which this reproduction occurs. To accomplish this result electrical connection between the two apparatus is required, and it is further required that the movement of tracing-point h' shall 55 be reproduced at the receiving-table with such precision and nicety that every shade of variation in its movement will be transmitted and repeated on the pointer at the receiving-station. The work on the receiving-table, therefore, is of a plastic or other suitable material, and the V-shaped tracing or graving point or tool h⁴ thereon is set to penetrate the otherwise even surface of the work in proportion as it is raised or lowered by impulses from 60 the tool h' of the sending apparatus—that is, the movements of h' are transmitted electrically and definitely to h⁴, so that when h' has

traversed the work before it h⁴ has reproduced an exact fac-simile thereof in like relief and outline, even to the slightest possible 70 elevation or depression, said reproduction being in lateral variation as well as vertical by reason of the V-shaped tool, though the whole is on an otherwise horizontal surface.

Two things are essential in this reproduction: first, that the work in both places shall move longitudinally and transversely at precisely the same rates of speed. The lateral movement is equalized by having feed-screws or other feed mechanism the same in both 80 places and the longitudinal movement by having the respective power-shafts which impel the carriage back and forth driven at the same rate of speed. Thus, if electric motors are employed in each place, they can be regulated or governed to run at certain predetermined revolutions per minute, and, being thus governed by suitable means connected with each motor and subject to local control, the reversal of both motors is effected simultaneously by or through lever H at the sending-station. This lever is described as having a contact g' for the local motor. Another contact g² is provided for the distant motor, and both contacts being made at the same 95 time the reversing mechanism of both motors will be operated at the same time. Then both carriages will start in the opposite direction together, and thus the action will be repeated until the work is done. Now, having the matter of movements for the work perfectly arranged, the next essential is to transmit the up and down vibrations of the lever H as they are produced from point h' and interpret the surface F to the receiving-point h⁴, so that the two 100 points will work in unison and rise and fall together and to the same elevations and depths. It will be understood that in this operation the sending-point h' rides over the surface of the work as it is found and does not penetrate 110 it, while the point h⁴ makes penetrations in the work of greater or less depth and width, according to the conditions of the surface reproduced—that is, when the point h' sinks low the point h⁴ will cut deep, and when the 115 point h' rides high the point h⁴ will cut light, and so on, the rise and fall of both being simultaneous. This reproduction of movements is effected by means of a current of 120 electricity proceeding from a battery or other suitable generator K through lever H to contact-screws k, spring-pressed pins k', and resistance-coils k², whence the wire leads to the main line and the receiving-station. As here shown, I employ five resistance-coils of gradually-decreasing size and resistance, and the 125 contact-screws are so set that the coil of greatest resistance is first thrown into circuit. Then at the receiving-station, at the outer extremity of lever H', are solenoids L L', wound in reverse directions, which, being thrown into the circuit when the current passes through any of the coils k, exert an attractive and 130 repellent force upon said lever in proportion to

the volume of the current. Thus, if the current has to pass through coil 1 of the series, where the resistance is greatest, the flow will be less than through any of the others, and 5 hence the attraction or pull on lever H' would be at the minimum. On the other hand, if the current were through coil 5 it would have its least resistance and greatest strength, and the pull on lever H' would be at its maximum. This would correspond to the highest 10 elevation in the play of point h' and the greatest resistance to the lowest depression or fall thereof. It will follow, of course, if contact is made at No. 5 that the other coils preceding 15 will all be in circuit, but the current will naturally choose the path of least resistance, and hence will pass through No. 5 exclusively, in preference to any of the others. In this way, also, I am enabled to get the graduation 20 of movement which is dependent on the graduation of current, the resistance-coils serving to break the strength of the current just sufficiently to answer my purpose. Of course any desired number of coils can be used and 25 arrangement thereof made that is convenient. As here shown, they are beneath the base A; but they might be on top or elsewhere about the apparatus. The spring-coils beneath pins k' make connection with the wires beneath. 30 The telescopic bar M, carrying the points k' , is pivotally secured at its inner end and vertically adjustable at its outer end, so as to adjust the pins k' simultaneous with respect to screws k , instead of setting each screw 35 separately when more or less range of vibration of lever H is wanted.

As before described, the frame E, having the raised portions at each end e , is placed upon the table, which reciprocates underneath 40 the tracing-point and feeds crosswise of such reciprocation at regular intervals. The said frame incloses or holds the model or the representation of the picture or sketch with its variable undulation. Now it will be observed 45 that the greatest height of these elevations does not reach to the same height as the thickened portions e of the frame E, so that when the tracing-point is moved to the highest position of the east the last of the contact-points 50 k is in circuit. There still remain the two outer contact-points which are not yet in circuit, but which are thrown into circuit the moment the tracing-point h' rides upon the elevation e , thus effecting the reversing and 55 stopping of both the local and distant table-actuating mechanism. This is accomplished as follows: The contact-point g' is insulated from the main - line circuit, which passes through lever II, its attached contact-points 60 k , and the respective resistances k^2 upon the line-wire to the receiving-instrument. This contact-point g' , when thrown in circuit by elevation e and tracing-point h' with a local battery and electro-magnets, is designed for 65 stopping and reversing the local conveying mechanism. The contact-point next inside of the one g' is in circuit at the same time, 70

but the current passing over it passes over the line-wire to the solenoids the same as the current which passed through the several contacts k as they successively were in circuit. This last contact-point allows the full strength of current to pass over the line and energizes the solenoids far beyond what the current was able to do in coming through the resistance-coils k^2 . Hence the armature-lever II moves to a greater degree even than is ever required of it in the transmission of the picture alone, thereby closing a local circuit for the receiving-station which is identical with the one for 80 the sending-station. Suitable clock mechanism, or its equivalent, is used as the motive power in either case. A pinion M is mounted outside of the bed-plate A upon the shaft b^2 . This pinion has meshing into it an intermediate gear, and this in turn receives motion from a pivoted train of gears 1 and 2, mounted upon a yoke, which has a depending lever which terminates in an armature. This lever has movement between the cores of two separate sets of magnets, and is normally held as 85 against either the one or the other of the sets by a spring 3. The gear 1, meshing with the intermediate gear, is in train with gear 2 of the same size, meshing with it, which gear 90 upon its hub on the opposite side of its support has a small pinion, which in turn meshes with a larger gear mounted upon the driving-shaft of the motor mechanism. The axial line of this motor-shaft is coincident with 95 a line drawn from center to center of the two gears mounted upon the outside face of the yoke, and the intersection of this line with their meeting pitch diameters, thus allowing small pinion 4 to remain in mesh with 100 the motor-gear 5 in whatever position the armature-lever is placed with respect to the electro-magnets. It will be observed that contact-point g' when in circuit as directed by elevations e at either end of the stroke of the 105 feed-table will actuate the armature and attract it against the electro-magnets. The gear 1, as now shown in mesh with intermediate gear, will when the armature is drawn to the opposite side of the magnets be out of mesh 110 with intermediate gear; but its companion mounted upon the yoke and being in mesh with itself will at this time engage the intermediate gear, and thus reverse the movement 115 of the feed-table. We will suppose the tracing-point to be upon the elevation e farthest to the right of Fig. 1, ready for the feed mechanism to begin its movement toward the left. At this point the electrical circuit will be closed through point g' , as described, leaving the gear 1 in mesh with the intermediate gear, thus having stopped the feed-machine and instantly reversing it so as to move in the opposite direction. When this occurs, the feed-table, of course, starts in the opposite 120 direction, as described, and when reaching the opposite end of its stroke the tracing-point h' is likewise raised or lifted upon the elevation 125 e , thus again closing the circuit through con-

tact-point g' and energizing the electro-magnet to draw the armature in the opposite direction. This is accomplished by means of a cut-out on the armature-lever, which, when the magnet on the one side has attracted the armature beyond its central position, as between the two sets of magnets, and to the one side of the central position, spring 3 cuts itself out of circuit and switches into circuit the opposite set of magnets, thus placing them in a position to be operated when the tracing-point has reached the opposite end of the feed mechanism. This movement is continued until the whole surface of the model has been gone over, when, of course, the machine is stopped.

It will be readily understood from the foregoing description that an apparatus thus constructed can be successfully employed at any distance between the sending and receiving stations for reproducing bas-relief surfaces in the manner described, and that the apparatus can as well be operated at greater distances as at less ones by simply supplying the necessary current for the purpose. The current is made variable or intermittent by the resistance-coils and the contact-points $k k'$, or, in other words, undulating with variations in volume and intensity according to the size of coil in circuit, as determined by the tracing-point h' yet unbroken in its flow.

The apparatus being started, it will run itself at both ends of the line until a particular piece of work is finished, when it is stopped.

If it were found practicable to employ an interrupted or intermittent current which in effect would be the same as is obtained through the graduated resistance-coils, that method might be employed instead of the coils; but I prefer the present arrangement to any other that now suggests itself. The function of these coils may of course be otherwise obtained, and the invention is designed to include any and all electrical agencies by which a current can be varied according to the undulations of the surface interpreted, and thus cause said surface to be reproduced at a distant point, as hereinbefore described. In the present construction the current is steady and constant, and is varied in degree or intensity as it goes out upon the line-wire by the resistance-coils.

The reproducing or interpreting arm H' , operated by solenoids $L L'$, may make its record through the medium of a ruling-pen—say of the usual style of a graving or tracing point or tool. In that case the pen would be held stationary on the paper or surface to be worked, and the lever or arm H would have a vertical play between the blades of the pen, on the stems of which are vertical inclines. The arm, playing up and down upon the inclines, would separate the blades or move them toward one another, according to the breadth of line wanted and the position of the arm on the inclines. Thus a line of any breadth desired can be obtained. The pen, of course, is

provided with a constant supply of ink and with a suitable spring or other means to restore the blades to their normal relation as against the action of the inclines. A bifurcated lever working on the outside of the pen-blades would in effect amount to a like operation.

The term "plastic material" as used in this specification should be interpreted as meaning such material as paraffine-wax, beeswax, the material employed for graphophone or phonograph tablets, and all like substances in which a graving-tool or sharp tracing-point will cut a clean score, trace, line, or groove into the material.

Having thus described my invention, what I claim as new, and desire to secure by Letters Patent, is—

85

1. The method of reproducing bas-relief, intaglios, and the like surfaces, consisting in running a tracing-point in contact with the surface to be reproduced and communicating the variable vibrations of said point to a reproducing point or device by means of an electric current, substantially as set forth.

2. The method of transmitting the configuration of a given surface from one point to another, which consists in causing a tracing-point to be vibrated by and according to the undulations of the surface to be reproduced and communicating the said undulations by means of an electric current to another tracing point or device working upon another surface, substantially as set forth.

95

3. The method of reproducing surfaces having variable elevations, the same consisting in moving the subject to be reproduced back and forth beneath a tracing-point and communicating the up-and-down movements of said point by an electric current to a reproducing point or device arranged over a surface in which the undulations of the original are faithfully reproduced by moving said material or work back and forth beneath the reproducing point or device by an electric current in unison with the original work, substantially as set forth.

105

4. The method of duplicating uneven surfaces, the same consisting in causing a tracing-point to travel back and forth in approximate paths over an undulating surface and causing a delineation of said surface to be made on another surface by a reproducing-point actuated by a current of electricity varying in strength with the varying elevations and depressions of the original surface, substantially as set forth.

115

5. The method herein described, consisting in reproducing an undulating surface on a body of plastic material having a substantially even surface by transmitting the undulations of the original surface electrically to the plastic surface through a suitable reproducing-point, arranged to penetrate said plastic surface to greater or less depth and width governed by the varying strength of the electric current, substantially as set forth.

125

130

6. The method herein described of working electrically from one surface to another, which consists in employing a suitable point for each surface and controlling one of said points 5 electrically through a series of graduated resistances, substantially as set forth. 65
7. In an electrical transmitting system, a subject having variable elevations on its surface and a tracing-point actuated by said elevations, substantially as set forth. 70
8. In an electrical transmitting system, a subject with an irregular surface and a tracing-point actuated by said subject, in combination with a plate having a reproducing-point actuated electrically through the movements of the tracing-point, substantially as set forth. 75
9. In an electrical transmitting system, two plates and a movable point for each plate, 20 with electrical connections, whereby one point is actuated by the variable movements of the other, substantially as set forth. 80
10. In an electrical transmitting system, a subject having an irregular or uneven surface and a tracing-point to work in contact therewith, in combination with a reproducing-point and electrical connections providing an undulating current for actuating the reproducing-point, substantially as set forth. 85
11. In an electrical transmitting system, a subject having a support provided with mechanism for moving it in different directions, a tracing-point pivoted to work up and down over said plate, and electrical connections 30 whereby said mechanism is reversed, substantially as set forth. 90
12. In an electrical transmitting system, a carrier for a subject provided with longitudinal and transverse ways, mechanism to move 40 the carrier in said ways, a tracing-point supported on an arm and having a spring to keep the point in working position, and electrical connections controlling the movements of said mechanism, substantially as set forth. 95
13. In an electrical transmitting system, a suitable support for a subject having an irregular surface, and an arm provided with a tracing-point adapted to work up and down over the subject, substantially as set forth. 105
14. In an electrical transmitting system, separate stations connected electrically, one of said stations having a subject or pattern with an irregular surface and a tracing-point actuated by said surface, and another station 55 having a reproducing-point actuated electrically, substantially as set forth. 110
15. In an electrical transmitting system, a sending-station having a tracing-point operated by an uneven surface over which said point is adapted to travel, in combination with a receiving-station having a reproducing-point to interpret said irregular surface, and electrical connections between said stations, provided with means to make the strength of the current correspond to the irregularities of the surface to be reproduced, substantially as set forth. 115
16. In an electrical transmitting system, sending and receiving stations electrically connected and a series of graduated resistances in said connections, substantially as set forth. 70
17. In an electrical transmitting system, a tracing-point adapted to vibrate and a point to reproduce said vibrations on a suitable surface, in combination with electrical connections provided with varying resistances and distinct contact-points, substantially as set forth. 75
18. In an electrical transmitting system, a tracing-point actuated by an irregular or undulating surface and an arm supporting said point, with an electrical contact-point on said arm to close a circuit and electrically control the propelling power of the local apparatus, substantially as set forth. 85
19. In an electrical transmitting system, a frame holding a subject to be reproduced having ribs or beads on which the tracing-point is adapted to ride, with said tracing-point, whereby the frame is reversed through electrical connections, substantially as set forth. 90
20. In an electrical transmitting system, a sending-station and a receiving-station, each 95 provided with suitable mechanism, and electrical connections between said stations whereby the said mechanism at both stations is simultaneously reversed, substantially as set forth. 100
21. In an electrical transmitting system, a receiving-station provided with a plate of plastic or like soft material having an even surface and a tool to work from said surface downward in lines varying in depth and width, 105 whereby a figure, picture, or the like is produced in relief on the said surface, and electrical connections with a sending-station for actuating said tool, substantially as set forth. 110
22. In an electrical transmitting system, a sending-station having a subject with arbitrary elevations on its surface and a tracing-point actuated by said elevations, in combination with a receiving-station having mechanism to interpret and reproduce the movements of the actuating tracing-point, substantially as set forth. 115
